COLLAPSIBLE SHIPPING CONTAINER

Gerald X. Garvey, Flushing, N. Y.

Application August 29, 1941, Serial No. 408,745

1 Claim. (Cl. 150—49)

This invention relates to shipping containers, and has for its object to provide shipping containers which can be readily made up to contain goods for shipping and which can be just as readily collapsed when returning to the place of origin, if returned in ballast. In either shipping or returning position these containers may be readily moved from place to place or from pier to steamer or vice-versa, by means of hydraulic or the like lift trucks. A container of this kind when filled with goods to be shipped has considerable weight, and when closed and sealed has a volumetric dimension, so that one container can be placed upon another, and side by side, like brick upon brick, and thereby the space in a hold or in a car, is fully utilized. Likewise, the improved container is constructed in such a way that the contour of the collapsed container is such that the collapsed containers can be placed parallel with each other, one on top of the other. But whether in shipping or in closed position, the structural features are so arranged that a lift truck can engage either a filled container, or one of several superposed empty containers, and move them from place to place.

The invention consists in a shipping container, comprising a collapsible structure adapted to be filled when extended and adapted to be collapsed when empty, said structure having a bottom which is flat when extended, and having parts hinged to each other and collapsible into substantial parallelism, uprights for said structure, extending below said bottom, and guide rods on the lower part of the bottom parts, said uprights and said guide rods being spaced to conform to the width and length of a standard lift truck, whereby both when filled and when collapsed, the container may be engaged by said truck lifted and moved from place to place.

The invention consists of other features of constructions which will be further described in connection with the embodiment shown in the drawing, and the invention will be finally set forth in the claim.

In the accompanying drawing—

Fig. 1 is a perspective view of my improved shipping container;

Fig. 2 is a section of the same, taken on line 2—2 of Fig. 1;

Fig. 3 is a detail section taken on line 3—3 of Fig. 2, when the container is in normal position at rest;

Fig. 4 is the same view, but showing it raised by a lift truck,

Fig. 5 is a front view of the frame as folded, and without the enclosing canvas envelope;

Fig. 6 is a detail section taken on line 6—6 of Fig. 1; and

Fig. 7 is a view of a form of swivel locks, to show the method of fastening to the canvas.

Similar characters of reference indicate corresponding parts:

Referring to the drawing, and more particularly to Figs. 1 to 4, the improved container is shown in Fig. 1, with the flap, which covers the front open side and the open top, in broken away form, all the rest of the sides, 10, 11, and 12 are formed of the canvas envelope. The part of the front flap which closes the front side of the container is indicated at 13, and the part of the flap which closes the top is indicated by 14. The edge of the part 14 is provided with a reinforcing strap 15 having a slot 15a, to be engaged by an eye bolt 16, and this by a padlock 15b whereby the container is entirely closed.

The structure of the containers consists of a bottom 20 formed of two matching members 21 and 22 each at their innermost ends having hinges 23 (see Fig. 5) which in turn are secured to a common central member 24. Each of the members 21 and 22, has at their outer ends, at their upper-sides, hinges 25, which in turn are secured to uprights, 26, 27, 28 and 29. The two uprights 26 and 27 are joined at their upper ends by a fixed bar 30, and the two uprights 28 and 29 are joined at their upper ends by a fixed bar 31. The uprights 26, 27, 28 and 29, extend at their lower ends below the bottom 20, as shown in Figs. 1 and 5. The upper ends of the uprights have equally sized bars hinged thereto and to each other, the upright 26 has a bar 33 hinged at 34, which bar 33 is hinged at 35 to another bar 36, which in turn is hinged at 37 to the upright 29. The upright 27 has a bar 38 hinged to it at 39. A bar 40 is hinged at 41 to a hinge 42 which joins the bars 38 and 40. A bolt lock 43 when bolted holds the bars 33 and 36 as well as the bars 38 and 40 from collapsing.

The canvas or the like walls 10, 11 and 12, are suitably secured to the inner surfaces of the posts or uprights 26, 27, 28 and 29, as shown by 44, as indicating any kind of suitable fastening means. The front side of the parts 26 and 29, the top sides of the fixed bars 30 and 31, and the rear bars 38 and 40 have swivel eyelets 48 arranged spaced from each other, as shown, and when the apron 45 which has its lowermost end at its edge permanently secured to the side of the bottom, covers the front and top of the con-

tainer, the eyelets 49, of the apron engage the swivel connections 48. A rope, or steel wire can then be passed through the eyelets of the swivels and have its ends jointed by a seal or lock, this being known as such and not shown. Thereby, a 5 sealed container can be easily provided, and by having its front and top opened it can be easily filled with various kinds of goods.

Horizontal supporting bars 80 are secured to each lateral edge portion of the members 21 and 22, to take up the weight of the contents in the bag. The lower surface of the bars are even with the lower ends of the uprights.

The pairs of uprights 26 and 27, and 28 and 29 are so spaced from each other, with the bars 80 in alignment therewith, that a lift truck of standard make may be passed below the bottom and be operated to lift the improved shipping container so as to move it from place to place. Not alone the width but the length of the container, also conforms to the width and length of the lift truck. Thus, the entire bottom (in distinction to the bottom heretofore referred to, and marked with the reference 20) is so constructed that the container can be moved by the truck.

In Figure 2 the lift truck is shown in plan, in dotted line. The frame 57 has rods 53, which rods operate in such a manner in respect to the rollers 56 (front and rear), that by the operation of the handle the rods 58 are operated and the rollers moved downwardly, whereby the truck and the container are raised, and can be moved by the rollers, upon pulling or pushing the handle of which the base 60 only is shown. The structure of such a lift truck is known and, per se, forms no part of this invention. However, it is the construction of the container for the purpose

of being engaged by a standard lift truck which constitutes the improvement and a container which can be readily filled, and when empty can be readily collapsed as shown, in Fig. 5. A group of such collapsed containers can be assembled and then engaged by a lift truck, the end disposition being always such as to be engageable by such truck.

The invention has been described, but changes may be made therein without departing from the spirit of the same as defined in the appended claim.

I claim:

A shipping container comprising corner uprights, a bottom hinged to the uprights at a distance from the dependent lower ends thereof, a vertically disposed envelope closing three sides of the box-like space formed by the corner uprights leaving an open space, and a vertically disposed apron detachably secured to the uprights bounding the open space, said dependent lower ends of the uprights being spaced apart a distance sufficient to allow a standard lift truck to engage the underside of the bottom and guide the lift truck between said dependent portions, said bottom being composed of two parts hinged together and adapted to collapse into substantial parallelism transversely to the truck guiding faces of the corner uprights forming the lift truck guides and between the same, members hinged to the top of said last-named uprights and to each other, so as to be aligned with each other and adapted to collapse into substantial parallelism with each other between said uprights, the envelope and apron having pleats in alignment with the hinged portion of the bottom to permit folding thereof upon the folding of the bottom.

GERALD X. GARVEY.
